LOADING BRIDGE

Harry Diamond, Elizabeth, N. J.

Application August 1, 1946, Serial No. 687,559

8 Claims. (Cl. 14—72)

1

This invention relates to loading bridges and more particularly to removable loading bridges adapted to be taken from one place to another.

The principal object of this invention is the provision of a loading bridge which is adapted to be moved by means of a small truck having a fork-shaped elevator at its forward end.

It will be understood that bridges of this type are extremely heavy and that several men are required to move them. In the present device means are provided whereby a single person operating a truck having a forked elevator may lift up the bridge, carry it from one point to another and then deposit it into operative position. This device has been developed for use in Naval installations and it has successfully been used in such installations.

Another object of this invention is the provision of a loading bridge of the character described which is adapted to span the gaps between loading and unloading platforms however wide or narrow these gaps may be within of course reasonable limitations.

A further object of this invention is the provision of a loading bridge of the character described which is adapted to be used between two platforms which are located at different levels, provision being made in said loading bridge to prevent accidental displacement thereof when used in connection with such platforms.

This application is a continuation-in-part of a prior application filed August 10, 1944, by the same applicant and bearing Serial No. 548,910 and since abandoned.

Preferred embodiments of this invention are shown in the accompanying drawing in which:

Fig. 1 is a plan view of a loading bridge as herein claimed;

Fig. 2 is a sectional view therethrough on the line 2—2 of Fig. 1;

Fig. 3 is a side view of said loading bridge;

Fig. 4 is a plan view, in enlarged detail, of one of the lifting handles by which a forked truck may raise, carry and lower the said loading bridge;

Fig. 5 is a sectional view on the line 5—5 of Fig. 6 showing a second form of lifting handle, a front view of the handle being shown; and

Fig. 6 is a sectional view on the line 6—6 of Fig. 5.

Referring now to Figs. 1 to 4 inclusive, it will be seen that the loading bridge herein claimed comprises a large plate 10 which is curved downwardly at one end 11 and which is curved, less pronouncedly at its opposite end 12.

A plurality of transverse and longitudinal ribs 15 and 16 respectively are welded to the underside of plate 10 to reinforce and strengthen it.

2

For the same purpose an I-beam 17 is also welded to the plate 10. Welded to the side edges of the plate 10 are a pair of stringers or side rails or guards 20. Affixed to one end of said stringers and affixed also to the ends of the I-beam 17 are a pair of vertically disposed pockets 21. At the opposite ends of the stringers 20 are affixed pins 22 and mounted on said pins are a pair of flanged locking bars 23. The opposite ends of said locking bars extend into the side pockets 21 and are adapted to float freely therein on vertical lines.

These locking bars 23 on their flanged portions are each provided with a series of holes 24 extending substantially their full length. Locking pins 25 are adapted to extend in part into and through said holes. It will be seen in Fig. 3 that these locking pins are somewhat U-shaped and that they have one long and one short leg, the two legs being readily positioned relative to each other by means of cross plate 27. The two legs are so spaced that they are adapted to enter adjoining holes 24 in the locking bars 23.

The loading bridge hereinabove described may be used as shown in Fig. 3 for example. In said figure the bridge is shown extending from a low platform 30 to a high platform 31. The loading bridge is so positioned that the pivoted ends of the locking bars 23 are situated adjacent the lower platform and the floating ends thereof adjacent the higher platform. The force of gravity acting upon the freely floating ends of said locking bars carries them downwardly until they rest against the bottom of the side pockets 21. In this position the locking bars are more nearly parallel to the top surfaces of the two platforms.

Such being the case, when the locking pins 25 are inserted into appropriate holes 24 of the locking bars, these pins engage the vertical side or edge of the lower platform 30 on substantially vertical lines. In other words the pins are substantially aligned with the vertical edge of the lower platform. This makes for a safe, non-slip engagement between the pins and the lower platform.

It will be seen particularly in Figs. 1, 2 and 4 that the loading bridge above described is provided with a pair of lifting handles 40. These lifting handles are substantially U-shaped and they are pivoted at the free ends of their legs by means of pins 41 to the adjacent longitudinal ribs 16. These handles are enclosed, when in inoperative position, within a pair of pockets 42. U-shaped openings 44 in the plate 10 which register with the U-shaped handles 40 when these handles are in inoperative position provide the openings from which these handles may be raised into operative position. This is clearly shown in Fig. 4. These U-shaped slots are enlarged at 45

to provide room for the fingers when it is desired to raise the handles 40 into operative position. The dot and dash lines 46 in Fig. 2 show the operative position of said handles. It will be seen that this operative position is substantially perpendicular with respect to the plate 10.

The spacing of the two handles corresponds to the spacing of the two arms which constitute the fork of trucks having conventional fork-shaped lifting apparatus. The two handles 40 when in the dot and dash position shown in Fig. 2, are adapted to receive the two arms of these trucks. It is a simple matter therefore to carry the loading bridge above described from one place to another.

In Figs. 5 and 6 another form of lifting handle is shown, to wit, the handle bearing character references 50. This handle like handle 40 is of U-shape. It is not pivoted however and the free ends of its two arms are affixed to a plate 51. Handle 50 is carried within a pocket 52 affixed to the bottom of the loading bridge. A slot 54 in the top plate of the loading bridge provides the passageway through which the handle 50 may be moved from the inoperative position shown by means of the solid lines in Fig. 6 to the operative position shown by means of the dotted lines 55 in said Fig. 6.

It will be seen in Fig. 5 that when the handle is in its inoperative position it is supported by a bracket 57. In Fig. 6 a flanged bracket 58 is shown which supports the handle when it is in operative position. As shown in said figure, the plate 51 of the handle 50 is adapted to rest upon the flange of flanged bracket 58, in order to support the handle in the operative position indicated by the dotted lines 55. In all other respects the loading bridge shown in Figs. 5 and 6 is similar to that shown in the first four figures.

It will be understood that this device may be modified in accordance with different requirements without any departure from the essential principles of the invention. For example, the several major parts of the loading bridge have been described as being welded to each other. It will be appreciated that any other method of affixing one part to another may be used.

I claim:

1. A loading bridge comprising a loading plate, a locking bar pivoted at one end to the side of the loading plate near one end of the plate and extending along the side of the plate toward the other end thereof, said locking bar having a plurality of holes therein and a locking pin disposed in one of said holes, the weight of the locking bar tending to swing the pin against an adjacent vertical surface of a loading platform.

2. A loading bridge comprising a loading plate, a locking bar pivoted at one end to the side of the loading plate near one end of the plate and extending along the side of the plate toward the other end thereof, a locking pin, and means to adjust the locking pin along the locking bar as desired, the weight of the locking bar tending to swing the pin against an adjacent vertical surface of a loading platform.

3. A loading bridge comprising a loading plate, a locking bar pivoted at one end to the side of the loading plate near one end of the plate and extending along the side of the plate toward the other end thereof, said locking bar having a plurality of holes therein and a locking pin disposed in one of said holes, the weight of the locking bar tending to swing the pin against an adjacent vertical surface of a loading plat-

75
4
form, and a pocket element disposed at the side of the loading plate with an open face receiving the end of the locking bar to guard and guide the same in its vertical free movement.

5. A loading bridge comprising a loading plate, a locking bar pivoted at one end to the side of the loading plate near one end of the plate and extending along the side of the plate toward the other end thereof, a locking pin, means to adjust the locking pin along the locking bar as desired, the weight of the locking bar tending to swing the pin against an adjacent wall of a loading platform, and a pocket element disposed at the side of the loading plate with an open face receiving the end of the locking bar to guard and guide the same in its vertical free movement.

10 15
6. A loading bridge comprising a loading plate, a flanged locking bar pivoted at one end to the side of the loading plate near one end of the plate and extending along the side of the plate toward the other end thereof, said locking bar having a plurality of holes along its flanged portion, and a locking pin disposed in one of said holes, the weight of the locking bar tending to swing the pin against an adjacent surface of a loading platform.

20 25
7. A loading bridge comprising a loading plate, a flanged locking bar pivoted at one end to the side of the loading plate near one end of the plate and extending along the side of the plate toward the other end thereof, said locking bar having a plurality of holes along its flanged portion, a locking pin disposed in one of said holes, the weight of the locking bar tending to swing the pin against an adjacent surface of a loading platform, and a pocket element disposed at the side of the loading plate with an open face receiving the end of the locking bar to guard and guide the same in its vertical free movement.

30 35
8. A loading bridge comprising a loading plate, a flanged locking bar pivoted to the side of the loading plate near one end of the plate with a series of holes in the flanged portion thereof, a U-shaped locking pin, the ends of the legs thereof extending through the holes in said flanged portion.

35 40 45
9. A loading bridge comprising a loading plate, a flanged locking bar pivoted to the side of the loading plate near one end of the plate with a series of holes in the flanged portion thereof, a U-shaped locking pin having legs of unequal length extending through adjacent holes in said flanged portion, and a cross plate extending between said legs to limit the extension of said legs into said holes.

HARRY DIAMOND.
